(57) **CLAIM**

The ornamental design for a vehicle center console, as shown and described.

DESCRIPTION

FIG. 1 is a perspective front view of a vehicle center console showing my new design;

FIG. 2 is a perspective rear view thereof;

FIG. 3 is a side view thereof;

FIG. 4 is a front view thereof;

FIG. 5 is a rear view thereof; and,

FIG. 6 is a top view thereof.

The broken lines illustrate portions of the vehicle center console that form no part of the claimed design.
